UNITED STATES PATENT OFFICE.

FREDRICK W. BROOKS, OF VIRGINIA, MINNESOTA.

RIVET-HOLDER.

1,317,348.

Specification of Letters Patent. Patented Sept. 30, 1919.

Application filed July 2, 1918. Serial No. 243,004.

To all whom it may concern:

Be it known that I, FREDRICK W. BROOKS, a citizen of the United States, residing at Virginia, in the county of Saint Louis and 5 State of Minnesota, have invented a new and useful Rivet-Holder, of which the following is a specification.

It is the object of this invention to provide a novel means whereby a rivet may be 10 held, in an inaccessible place, while the rivet is being butt-ended.

It is within the province of the disclosure to improve generally and to enhance the utility of devices of that type to which the 15 present invention appertains.

With the above and other objects in view, which will appear as the description proceeds, the invention resides in the combination and arrangement of parts and in the 20 details of construction hereinafter described and claimed, it being understood that, within the scope of what is claimed, changes in the precise embodiment of the invention shown can be made without departing from 25 the spirit of the invention.

In the accompanying drawings:

Figure 1 shows in end elevation, a portion of a boiler whereunto the device forming the subject matter of this application has 30 been applied, parts of the boiler being broken away;

Fig. 2 is a fragmental section on the line 2—2 of Fig. 1;

Fig. 3 is a cross section showing the holding device mounted on the boiler in a way which differs slightly from the way in which the structure is mounted in Fig. 1;

Fig. 4 is a perspective view showing the holding lever;

Fig. 5 is an end elevation of the lever;

Fig. 6 is a plan of the lever;

Fig. 7 is a cross section on the line 7—7 of Fig. 6;

Fig. 8 is a cross section on the line 8—8 of 45 Fig. 6; and

Fig. 9 is an elevation showing the fulcrum bolt.

In the accompanying drawings, the numerals 1 and 2 denote the end members of a 50 boiler provided with tubular flanges 3. The end members 1 and 2 are supplied with openings 5 adapted to receive stay bolts 6. Let it be assumed that it is desired to connect the tubular flanges 3 by means of rivets 55 7 and that it will be somewhat difficult, in the absence of the device hereinafter de-

scribed, to hold the inner ends of the rivets 7 while the outer ends thereof are being butt-ended. The device forming the subject matter of this application has been 60 shown, by way of illustration, as being used in connection with a portion of a boiler, but it is of course to be understood that the structure is capable of many uses, other than the one specified.

In carrying out the present invention there is provided a lever 8 supplied at one end with a broadened head 9, the other end of the lever preferably being curved as shown at 10. Intermediate its ends, the lever is broadened to form an anvil 11 at the sides of which, projecting wings 12 are located. A recess 14 extends entirely through the head 9, and in the head, there are transverse openings 15, disposed at right angles 70 to the axis of the recess 14. The extremity of the part 10 of the lever is supplied with a hole 16. A pivot member preferably in the form of a bolt 17, may be mounted for adjustment in any of the openings 15, the pivot 80 member being mounted in any selected pair of the openings 5 of the members 1 and 2. In this way, the lever 8 will be fulcrumed on the members 1 and 2 for swinging movement transversely of the tubular flanges 3 85 which form the fire door hole 4.

The invention includes a fulcrum bolt 18 comprising a head 19 and a shank 20. The head 19 of the fulcrum bolt 18 has any desired number of openings 21. The head 19 90 of the fulcrum bolt may be placed in the recess 14 of the lever 8 and the pivot member 17 may be mounted for adjustment, in either of the openings 21 in the head 19 of the fulcrum bolt. The shank 20 of the fulcrum 95 bolt 18 may be inserted through alined rivet holes 22 in the boiler parts 1—2, as shown in Fig. 3, a nut 23 being threaded on the inner end of the shank 20. Thus, the lever 8 is fulcrumed in a manner which differs slightly 100 from that shown in Fig. 1.

One end of a flexible element 24 is mounted in the hole 16 of the lever and extends laterally, between the end members 1 and 2, to a point at one side of the boiler. If desired, the flexible element 24 may be extended outwardly through one of the openings 5 in the part 1.

The outer end of the flexible element 24 may be mounted on a hook 25 constituting a 110 part of a chain 26 connected with a finger 27 on a lever 28, the lower end of the lever be-

ing fulcrumed on a cleat 29 mounted on the floor. The lever 28 and attendant parts constitute a tightening device, and this tightening device may be of any desired form adapted to put the flexible element 24 under tension.

When the lever 8 is fulcrumed as shown in Fig. 1 or is fulcrumed on the bolt 18, as shown in Fig. 3, the head of a rivet is engaged with the anvil 11 of lever, between the wings 12. When tension is exerted on the flexible element 24, the lever will be held in place, so as to retain the rivet, and the rivet may be butt-ended readily. Since the head 9 of the lever is provided with a plurality of openings 15, and since there are several openings 21 in the head 19 of the fulcrum bolt 18, it will be obvious that many adjustments may be made, so that the anvil 11 may be positioned properly with respect to the head of the rivet which is to be upset.

Having thus described the invention, what is claimed is:

1. A device for holding rivets during the heading thereof, comprising a lever provided intermediate its ends with an anvil for the rivet; means for securing and fulcruming one end of the lever pivotally but detachably upon the structure wherein the rivet is to be inserted; and means for applying tension to the other end of the lever.

2. A device for holding a rivet in a tube, comprising a lever provided intermediate its ends with an anvil for the rivet and curved to extend part way around the tube; mechanism for fulcruming the lever at one end; and means for operating the lever from the other end thereof, said means and said mechanism being spaced to admit the tube therebetween.

3. In a device for holding rivets, a lever provided at one end with a recess and hav-

ing an anvil intermediate its end; a pivot member mounted in the lever and extended across the recess; a fulcrum element having one of its ends mounted in the recess and mounted to swing on the pivot member; and a tightening device assembled with the other end of the lever.

4. In a device for holding rivets, a lever provided at one end with a recess and having a plurality of transverse openings communicating with the recess, the lever being provided intermediate its ends with an anvil; a pivot member adapted to be mounted in any of the openings, and extended across the recess; a fulcrum element having one of its ends disposed in the recess, said end of the fulcrum element having a plurality of openings, in any one of which the pivot member may be mounted; and a tightening device assembled with the other end of the lever.

5. In a device for holding rivets, a lever provided intermediate its end with an anvil and having projecting wings located on each side of the anvil, there being a recess in one end of the lever and said end of the lever being supplied with a plurality of openings communicating with the recess; a pivot member adapted to be mounted in any of the openings, and extended across the recess; a fulcrum element having one of its ends disposed in the recess, said end of the fulcrum element having a plurality of openings, in any one of which the pivot member may be mounted; and a tightening device assembled with the other end of the lever.

In testimony that I claim the foregoing as my own, I have hereto affixed my signature in the presence of a witness.

FREDRICK W. BROOKS.
